[57] CLAIM

The ornamental design for a handle for kitchen utensils,
as shown and described.

DESCRIPTION

FIG. 1 is a top plan view of a handle for kitchen utensils, showing my new design, the bottom plan view
being a mirror image thereof;

FIG. 2 is a side elevational view thereof, the opposite
side being a mirror image thereof;

FIG. 3 is a rear elevational view thereof; and

FIG. 4 is a front elevational view thereof.
